ABSTRACT

A series of switches are used to operate a series of electrically operated valves. Some of the valves are normally open and some are normally closed and if the incorrect switches are operated a valve will be moved to its opposite state and thus prevent the flow of fuel to the engine.

ANTI-THEFT OR USE DEVICE FOR SELF PROPELLED OR STATIONARY ENGINES

BACKGROUND OF THE INVENTION

The present invention was designed to be used as an anti-theft device for automobiles or other self-propelled vehicles, and also to prevent the unauthorized use of stationary engines.

Inherent in the use of the device is its use as an anti-theft device for automobiles. When properly installed, the device of the present invention will stop the theft of a car by all but the professional auto thief. Even the professional thief, or even one who knows the device thoroughly, will be discouraged from stealing the car because he will know that it takes considerable time to bypass the device or to break its code.

A car equipped with the device of the present invention can be started in the usual manner but it will run for only a short time until the carburetor is emptied of fuel. A thief attempting to restart the car at this time by trying different code combinations will run the battery down after several trials since, with the carburetor empty, considerable cranking is necessary just to refill it before the engine will start. If the right combination is not found within the first few trials, the battery will soon be too low to crank the engine. Thus the unauthorized use of the engine, or of the automobile, will be prevented.

SUMMARY OF THE INVENTION

The device of the present invention comprises a series of electrically operated normally open and normally closed valves which may be assembled in any desired order and only the normally closed valves may be operated by means of the control switches to allow the flow of fuel to the engine.

An object of the present invention is to prevent the theft or use of self-propelled or stationary engines by obstructing the flow of fuel to the engine with a control that is simple to operate yet difficult for an unauthorized user to circumvent.

It is a further object of the present invention to combine a control assembly and a valve assembly wherein disassembly of the control assembly will not reveal the code that must be used to operate only the correctly predetermined valves to allow the flow of fuel to the engine.

BRIEF DESCRIPTION OF THE DRAWINGS

Additional objects and advantages of the invention will become apparent upon full consideration of the following detailed description and accompanying drawings in which:

FIG. 1 is an elevation view of the overall device partially in section;

FIG. 2 is a perspective view of the valve assembly portion of the device of FIG. 1;

FIG. 3 is an enlarged partially sectioned view of a normally closed valve shown in place in FIG. 1;

FIG. 4 is an enlarged partially sectioned view of a normally open valve shown in place in FIG. 1;

FIG. 5 is a side elevational view of the valve of either FIG. 3 or FIG. 4; and

FIG. 6 is an electrical schematic diagram of the control assembly portion of the device of FIG. 1.

DESCRIPTION OF THE PREFERRED EMBODIMENT

Referring first to FIG. 1 wherein is shown of the valve two main parts comprising the present invention, there is shown a control assembly 10 connected by cable or wiring harness 11 to the valve assembly 20. The control assembly 10 in the preferred embodiment is composed of a series of push buttons 12 with one push button 12 for each of the valves 21 in valve assembly 20. Operation of the correct push button 12 will by electrical connection through cable or wiring harness 11 activate solenoid coil 22 mounted above valves 21 and allow fuel to flow through fuel line 23. A reset-hold switch 13 is included on the control panel to be used to hold the control voltages so that the valves do not have to be reset after the ignition has been turned off. This is done so that a car can be left in a parking lot and still be operated without knowing the code as to which push button should be operated and in what order these push buttons should be operated. A light 14 is provided to remind a person when the reset-hold switch 13 is in the hold position since anyone can drive the car away when it is in this position or can operate the stationary engine, as the case may be.

FIG. 2 shows the valve assembly 20 in a perspective view thereof as it might look when the assembly for example, in an automobile. On opposite sides of the assembly of valves 21 are located blocks 24 which are used at each end of the valve assembly 20 to bolt the valve body 21 together and serve as the interconnecting link between the fuel line 23 and the valve bodies 21. A cover 19 is placed over and covers the solenoid coils 22.

The valve assembly is composed of a series of normally open valves such as valve 25 and normally closed valves such as valve 26. To normally open, fuel to flow through lines 23, all of the normally closed valves 26 must be opened and all of the normally open valves 25 must be left open. If one normally closed valve 26 is left closed or one normally open valve 25 is closed, the fuel will be blocked and the engine will stop. The total number and sequence of these valves determines the code for the device of the present invention. Assume for instance that there are two normally open valves 25 and three normally closed valves 26 in the valve assembly. Assume also that they are in the following order: No. 1 normally closed, No. 2 normally open, No. 3 normally open, No. 4 normally closed, No. 5 normally closed. To operate the engine and thus operate the automobile in which the engine is installed, control buttons 1, 4 and 5 must be pushed, and only 1, 4 and 5. To make it more difficult for an unauthorized person, the control may be wired to require that push buttons 1, 4 and 5 be pushed in the following sequence 4, 5, 1. To operate the engine and the automobile in which the engine is installed, one would therefore have to push buttons 1, 4 and 5 and push them in proper sequence of 4, 5 and 1. Any other combination or sequence would fail to operate the engine.

FIGS. 3, 4 and 5 show enlarged views of the assembly of single valves.

FIGS. 3 and 4 show the assembly of a normally closed valve and a normally open valve respectively and FIG. 5 shows a side elevational view of either of the valves since the valves are not distinguishable from each other by their outward appearance.

The assembly of a single valve consists of a valve body 30 which is the same whether used with the normally closed valve 26 of FIG. 3 or the normally open valve 25 of FIG. 4. Thus the side elevation view of valve body 30 as shown in FIG. 5 is applicable to both FIGS. 3 and 4. Mounted on valve body 30 is solenoid coil 22 with solenoid shell 31 passing through its center. The bottom portion 32 of solenoid shell 31 fits into the top opening in valve body 30. A plug 33 closes a similar shaped opening on the bottom of valve body 30.

Valve body 30 is constructed so as to accept either a normally closed or a normally open valve. The normally closed valve with valve stem 34 and head 35 is installed from the top end before insertion of solenoid shell 31. In the normally open valve the valve stem 36 with head 37 is installed from the bottom after which plug 33 is inserted in the opening in valve body 30. With the valve stem and head in place the solenoid shell 31 and the plug 33 are press fitted, or otherwise assembled, into the top and bottom of the valve body 30 respectively. The solenoid coil 22 is then fitted over solenoid shell 31. When bolting the single valve assemblies together, they are arranged so that the fuel flows into the upper chamber on the normally closed valve 26 and into the lower chamber on the normally open valve 25 as designated by arrows in the Figures. Energizing a solenoid coil 22 will close a normally open valve 25 or open a normally closed valve 26.

In the valve body 30 passageway 38 from upper chamber 39 slopes downward from chamber 39 and passageway 41 from lower chamber 42 slopes upward from chamber 42. Both passageways 38 and 41 have the center lines of their openings on the surface of valve body 30 on the same center line through valve body 30 in order to fit to the adjacent valve body which is placed in a 180° rotated position (or alternatively an inverted position) from the adjacent valve body as shown in the cutaway of valves 25 and 26 of FIG. 1.

Any number of single valve assemblies may be bolted together for a complete assembly. The combination of normally open and normally closed valves may be varied to give as many different codes as possible.

The device of the present invention has been illustrated in FIG. 1 with eight push buttons 12 on control assembly 10 for the eight valves in valve assembly 20. The schematic diagram of FIG. 6 has been drawn to show a control assembly for eight valves. The schematic is then basically divided into eight identical sections, except for the hold-reset switch SW1, hold light PL10, and the steering diodes SD1 to SD4. Circuit description will be given for one of these sections to describe the operation of one individual solenoid valve.

When the car's ignition switch is turned on, battery voltage is applied to one end of the solenoid coil L101. The valve does not operate, however, and the control rectifier CR101 must be turned on to complete the circuit. Control rectifier CR101 is turned on by pushing pushbutton PB101. This applies a voltage to the gate of control rectifier CR101 through voltage dividing resistors R101, R102, and R103. The voltage on the gate of control rectifier CR101 turns it on completing the circuit through coil L101 and diode D101 operating solenoid valve number one. The control rectifier needs only a momentary voltage applied to its gate to turn it on and it then stays on until the anode voltage is removed. This is done by turning the ignition off. In normal operation all control rectifiers are turned off when

the ignition is turned off. This means that each time the ignition is turned on to start the car the code for the present device must be set into the control.

Provision has been made so that the code may be held in the control independent of the position of the ignition switch. To do this, the ignition switch is turned on and the proper code set. The hold-reset switch SW1 is flipped to the hold position. The ignition can now be turned off and on without operating the device. A hold light PL10 will burn continually when switch SW1 is in the hold position to warn the driver that the car is not protected by the device.

Turning switch SW1 to the hold position applies a voltage to the anode of CR101 through diode D10 and resistor R104. This keeps a voltage on the anode of CR101 when the ignition is turned off preventing control rectifier CR101 from turning off. Resistor R104 is a current limiting resistor allowing only enough current to flow through control rectifier CR101 to keep it on and prevent excessive drain on the battery. Diode D10 prevents current flowing from the ignition switch through L101, D102, and lighting hold light PL10 when hold-reset switch SW1 is open. Diode D102 prevents excessive voltage being developed across L101 when ignition is turned off.

Steering diodes SD1 to SD4 are used to set in switching sequence of the push button control. An example of operation is as follows. Connecting the cathode of diode SD4 to the anode of control rectifier CR801 and the anode of SD4 to the common point of R603 and R602 makes it impossible to turn on CR601 after CR801 has been turned on. Turning on CR801 first shorts any current from the common point of R603 and R602 through CR801, thus preventing any voltage from being applied to the gate of CR601. This makes it necessary to turn on CR601 before turning on CR801. The steering diodes can be wired in to accomplish any desired sequence of operation desired.

Push buttons 12 are spring loaded so that they will always return to their normal position when released. This is done so that they will in no way reveal the code which is used to operate the appropriate valves. The code must be reset into the control when the ignition switch is again turned on and the above sequence of operations described in connection with FIG. 6 again takes place.

Further advantages of the device of the present invention lie in the use of the solid state circuitry wherein it is quite difficult to determine the sequence of the normally open and normally closed valves and in addition once the valves have been assembled it is very difficult to determine which are normally open and which are normally closed since all valve bodies have the same exterior appearance.

It will be obvious to those skilled in the art that various changes will be made without departing from the scope of the invention and the invention is not to be considered limited to what is shown in the drawings and described in the specification.

What is claimed is:

1. A fuel cutoff device comprising a plurality of serially connected valves including at least one normally closed valve, and at least one normally open valve, each of said at least one normally closed valve and each of said at least one normally open valve having means to operate said valve including

a solenoid coil mounted on said valve to move said valve from its normal position;
 a switching means operated from a control panel and connected electrically to said solenoid,
 a voltage divider in series with said switching 5 means,
 a control rectifier with a gate electrode connected to an intermediate point on said voltage divider and its anode connected to said solenoid;
 power supply means connected to the anode of said 10 control rectifier through said switching means;
 and ignition switch means connected to said power supply means in series with each of said switching means.

2. The fuel cutoff device of claim 1, further characterized by 15

there being at least two normally closed valves, and at least one diode having its cathode connected to said anode of said control rectifier of one of said operating means of said normally closed valves and its anode connected to another intermediate point on said voltage divider of another one of said operating means of another of said normally closed valves 20

whereby a sequence of operation is determined. 25

3. The fuel cutoff device of claim 1, further characterized by

a holding switch means to retain switching means settings when said ignition switch means is shut off, said holding switch means connected to said power 30 supply means in parallel with said ignition switch means.

4. A full cutoff device comprising a plurality of serially connected valves including at least one normally closed valve, and at least one 35 normally open valve,

both said normally closed valve and said normally

open valve presenting similar outer appearances, each of said at least one normally closed valve and each of said at least one normally open valve having means to operate each said valve including solenoid means positioned to move each of said valves individually from its normal position, a switching means operated from a control panel and connected to said solenoid means, said plurality of valves having a continuous open passage through all of said plurality of valves upon operation of said switching means to operate said solenoid means only to each of said at least one normally closed valve, power supply means and ignition switch means connected in series with each of said switching means.

5. The fuel cutoff device of claim 4, further characterized by

each of said valves having a similar shaped valve body, said valve body having an upper chamber and a lower chamber connected to each other, a downward sloping passageway connecting to said lower chamber from one side of said valve body, an upward sloping passageway connecting to said upper chamber from the other side of said valve body, said passageways having openings to the opposite sides of said valve body on the same center line through said body.

6. The fuel cutoff device of claim 5, further characterized by

a valve head positioned in said upper chamber of said normally open valve, and a valve head positioned in said lower chamber of said normally open valve.
